1 Claim. (Cl. 39—7)

This invention pertains to crossing barriers, and more particularly to automatic and multiple safety gate and signal systems.

In safety barrier systems, the most satisfactory method of guarding a railroad crossing, there are a number of problems which must be solved. First of all, an adequate crossing barrier must be provided which is positive in operation, affords adequate protection, and operates on the safety side, being preferably automatically controlled by the approaching track vehicle. Obviously, crossing barriers which are manually operated, even though the first cost may be less than that of an automatically controlled barrier, are more expensive in the long run since an attendant must always be at the crossing to raise and lower the crossing gates at the approach of a train, this attendant must be sheltered, and some means provided whereby the approach of the train is indicated to him. Another consideration is that the crossing gate must be as inexpensive as possible, for at least two gates must be installed at a crossing.

With the old type of gates, if a road vehicle is trapped between the lowered crossing gates, the road vehicle is either hit by the approaching train or must break through the crossing gate, causing damage to either the gate or the vehicle, or both, so that it is desirable that there be some safety feature connected with the gate whereby the gate can be rendered inoperative for a short period of time to take care of any emergency whereby a motorist is trapped between the gates when in lowered position, and this safety feature preferably should not involve the raising and lowering of the gates, as this is slow and opens the crossing where a train is approaching.

Where the crossing gates are controlled automatically, means must be provided wherein the gates will operate though there be a failure of the power ordinarily used to operate the gates.

There are other contingencies which may arise which should be taken care of for the crossing gate to be successful, one of which is the condition wherein the gates may be lowered and strike, say, the upper portion of a road vehicle. This frequently occurs where the motorist approaches at too great a speed and so is not able to stop in time.

As has already been pointed out, it is a most desirable thing to have the gates operated by the track vehicle, in which case a system of control must be provided wherein the gates are operated at different speeds or at different time intervals, depending upon the speed of the track vehicle,

and also some means must be provided for the operation of the gates where the railway crossing is adjacent a siding, which siding may be used more or less permanently.

It is therefore an object of this invention to provide a barrier construction which, while effective to provide safety means at a crossing, is still yieldable under impact and/or obstruction.

Another object of this invention is to provide a crossing barrier which is automatically controlled in a manner to be dependent upon the speed of the approaching track vehicle.

A further object of this invention is to provide a crossing barrier which, though positive in operation, is operable in a manner whereby jarring of the barrier is prevented.

A still further object of this invention is to provide a crossing barrier system wherein a plurality of means of operation is provided, one of which is normally inoperative and which is only operative upon failure of the normally operative means.

Yet a further object is to provide a barrier and system of operation therefor which fulfill all requirements of manufacture and service.

With these and various other objects in view, the invention may consist of certain novel features of construction and operation, as will be more fully described and particularly pointed out in the specification, drawings and claim appended hereto.

In the drawings, which illustrate embodiments of the device and wherein like reference characters are used to designate like parts—

Figure 1 is a fragmentary sectional elevation through the improved crossing barrier;

Figure 2 is a fragmentary sectional elevation through the barrier shown in Figure 1, the same being taken substantially on the transverse center line thereof, and at substantially ninety degrees to the construction shown in Figure 1;

Figure 3 is a side elevation of the construction shown in Figure 1 wherein the sidewalk gate is omitted, and the shock absorbing device is shown as applied to the road barrier;

Figure 4 is an end elevation of the device shown in Figure 3;

Figure 5 is a transverse sectional elevation through a modified form of barrier;

Figure 6 is a side elevation of the control brake for the gates;

Figure 7 is a side elevation of the control switch for the constructions;

Figure 8 is a sectional elevation taken at sub-

stantially ninety degrees to the construction shown in Figure 7;

Figure 9 is a wiring diagram of a form of track circuit which may be used with the gate constructions illustrated in Figures 1 to 8 inclusive;

Figure 10 is a wiring diagram for A. C. operation of the motors in the form of gate illustrated in Figures 1 to 4 inclusive;

Figure 11 is a wiring diagram for A. C. and D. C. operation of the motors in the constructions shown in Figures 1 to 4 inclusive;

Figure 12 is a wiring diagram for A. C. operation of the motor in the form of gate illustrated in Figure 5;

Figure 13 is a wiring diagram for A. C. and D. C. operation of the motor in the form of gate illustrated in Figure 5.

Referring first of all more particularly to the constructions shown in Figures 1 and 2, the standard or pedestal 10 is provided with a base 12 having secured thereto the support 14 forming a foundation to which the D. C. motor 16 and the A. C. motor 18 are secured, the standard being provided with suitable cover plates 20 and 22 forming convenient means of ingress to the operating mechanism. The standard 10 is provided with the casing 24 secured to the casing 26 supported on the lower portion of the standard 10. The casing 26 is provided with the bearing recess 28 adapted to receive the anti-friction bearings 30 which consist of the outer race ring 32 disposed in said recess, and the inner race ring 34 disposed on the multiple tube 36 and adapted to rotate therewith, suitable rollers 38 spaced by the usual cage being interposed between the inner and outer race rings.

The multiple tube 36 is secured as at 40 to the head 42, the anti-friction bearings being arranged to support the head of the multiple tube 36 for rotation with respect to the standard, the multiple tube being on the vertical center line of the assembly. A suitable bushing 44 is provided between the multiple tube and the head 46 enclosing the top of the casing 26, the head 42 being provided with a depending skirt 48 embracing the casing 26 and the head 46 to prevent ingress of moisture, the enlarged plug 50 being provided in said skirt for adjustment of the securing means 40. The inner tube 52 of the multiple tube assembly is mounted on anti-friction bearings 54 and 56 shown as of different character disposed between the outer tube of the multiple tube assembly, the inner tube extending downwardly and being provided with the gear 58 meshing with the gear 60 provided on the sprocket shaft 62, the sprocket shaft being adapted to be rotated through suitable sprocket and chain connections 64 and 66 by either the D. C. or A. C. motor.

The sprocket shaft is mounted on anti-friction bearings 68 and 70 provided in the housing 24. The gear 60 meshes with the gear 72 mounted on the upwardly extending shaft 74, the lower end of said shaft being provided with the worm 76 meshing with the gear 78 which is adapted to operate the control switch 80. The shaft 74 extends through the casing 24 and adjacent the upper end thereof is coupled as at 82 to the shaft 84 provided on the gear casing 86 secured as at 88 to the upper casing 26. The casing 86 is provided with the jack shaft 90, the inner end of which is connected through the gear 92 to the gear 94 provided on the shaft 84. The outer end of the shaft 90 is channeled as at 96 in the

casing 86, the shaft being provided with the worm 98 meshing with the gear 100 provided on the crank shaft 102. The crank arm 104 is disposed outwardly of the casing and is linked through the link 106 loosely as at 108 to the bracket 110 provided on the sidewalk arm 112. The sidewalk arm is pivoted as at 114 to the casing 86, the casing being provided with spaced stops 116 and 118 for limiting upward and downward movement of the sidewalk arm.

The shock absorbing device 120 is secured to the head 42, though a bracket may be disposed on the casing 26 for this purpose, the shock absorber 120 being adapted to engage a track 122 provided on the road arm 124. The shock absorber is adapted to engage the arm at approximately forty-five degrees from the horizontal and comes to rest against the gate stop angle 126 mounted on the bracket 128 provided on the head. The bracket also serves to support the bracket 130 secured to the shock absorber 120. The shock absorber 132 is secured to the casing 26 and is provided with the arm 134 adapted to be engaged by the road arm 124 on up movement thereof, the engagement being at about thirty-five degrees from the vertical and coming to rest on the lower buffer bracket 136 provided on the casing 26. The road arm 124 is provided with a suitable rack 138 provided in the track 140 provided on said road arm and engaging the pinion 142 provided on the shaft 144. The shaft is mounted in anti-friction bearings 146 adapted to be lubricated through the fitting 148 communicating with the lubricant recess 150 mounted in the head. The shaft is provided with the pinion 152 mounted between the anti-friction bearings 154 provided in the supporting brackets 156, the pinion meshing with a worm 158 mounted on the hollow shaft 52, with an arrangement such as disclosed in application Serial No. 450,991, filed May 9, 1930.

The gate is adapted to be operated by a movement of translation, causing an unbalancing of the gate arm, permitting its up and down movement. In order to delay the up movement of the gate a down lock 160 is provided. The down lock 160 consists essentially of a bracket 162 secured to the stop 126, the bracket being provided with the latch member 164 pivoted as at 166 and normally urged outwardly by means of the spring 168. The road arm is provided with the bracket 170 adapted to engage the latch member 164. With this arrangement the gate will have to be moved laterally until the bracket 170 disengages the latch which will permit the gate to be raised. The multiple tube 36 is provided with the gear 172 meshing with the gear 174 mounted on the jack shaft 176, the gear 174 being connected and yieldably held in normal position by means of the spaced springs 178, all in accordance with the above identified application.

Should the road arm be struck, the head will pivot around the multiple tube to compress either of the springs 178, permitting yieldable movement of the head, the springs causing the head to return to its normal position when pressure is removed from the road arm. Operation of the motors through the switches will cause the shaft 62 to be revolved, which will revolve the shaft 52 to cause the worm 158 to rotate the pinion 152. Rotation of the pinion, assuming the gate to be in up position, will move the gate through the rack and pinion 138 and 142 with a slight movement of translation until the gate is

in an unbalanced position to rotate around the shaft 144 to its downward position. The downward movement is resisted at forty-five degrees by engagement with the arm of the shock absorber 120 until the gate finally is cushioned to rest against the bracket 126. At this time, the latch 160 engages the latch bracket 110. Reversal of movement of the motors will cause a reverse movement through the parts enumerated, but the gate will not immediately start in its upward motion until a sufficient movement of translation has occurred to release the bracket 110 from the latch 160. Upon release of the bracket from the latch the gate will immediately start downwardly, the motion adjacent its final position being resisted by the arm 134 of the shock absorber 122 until it is finally brought to rest against the brackets or stops 136.

In the form of the device shown in Figure 5, the pedestal 200 is provided with the head 202. The head 202 is of such construction as to contain the A. C. and D. C. motors 204 and 206, the motors being provided with suitable pinions 208 meshing with the gear 210 mounted on the shaft 212. The shaft 212 is mounted in the lubricant casing 214 and meshes with the gear 216 mounted on the vertical shaft 218. Suitable anti-friction bearings 220 serve to mount the shaft in the lubricant casing. The shaft is provided with the worm 222 meshing with the suitable gear 224 mounted on the gate arm shaft 226, the shaft being anti-frictionally mounted at 228 in suitable lubricant recesses 230 formed in the head. Pinions 232 are mounted on the shaft 226 and are adapted to be engaged by the racks 234 mounted in suitable tracks 236 on the gate arm 238.

This gate is of such construction that it is provided with only one arm. This gate may be provided with the upper stops 240 and the lower stops 242, as well as the shock absorbers (not shown) and the latches (not shown). The shaft 218 extends downwardly and is coupled as at 244 to the control switches 246 to be later described.

In the operation of this gate, actuation of either of the motors rotates the shaft 212 through the gears 208 and 210, causing rotation of the shaft 218 until such time as the switch 246 cuts off the current to the motor. Rotation of the shaft 218 rotates the shaft 226 to cause the movement of translation and rotation of the gate to down position. Up position, of course, occurs upon reversal of the motors, it being understood that reversible motors are used in this and in the other modification.

Referring now more particularly to the switch mechanism illustrated in Figures 7 and 8, this form of switch mechanism is adapted for operating either of the gates illustrated and described, it being only necessary to change the number of contacts provided thereon. In the construction illustrated in Figure 1, the switch of course is operated directly by the shaft 74.

In the construction illustrated in Figure 5, the switch is adapted to be operated by the shaft 218. The switch consists essentially of a securing base 250 provided with spaced supporting arms 252 in which the shaft 254 is rotatably mounted. The shaft is adapted to be operated by the pinion 256 meshing with a suitable worm or gear provided on the operating shafts above described. The shaft 254 is provided with a suitable number of non-conductor cams 258 adjustably mounted on said shafts, as by means of the nuts 260. An insulating bar 262 is carried by

the bracket 252 and suitable contact fingers 264 and 266 are mounted for electrical connection to the respective motors, engagement between the fingers 264 and 266 being controlled by movement of the cam 258 determining operation of the respective motors. Operation of the motor, therefore, depends upon the engagement between the cam switches 258 and the contact fingers 266. Engagement between the different cams and their respective contact fingers determines the operation of the motor. It will be appreciated that the switch fingers 264 and 266 are normally urged away from each other. That is, they will assume the position of the fingers 264 in the dotted line position of the finger 266 as shown in Figure 7, breaking the contact and rendering the motor inoperative. Movement of the cam to cause contact between the fingers closes the circuit to cause operation of the motor. Adjustment of this type of switch is very easily and quickly effected, due to the fact that it is only necessary to loosen the lock nut 260 to adjust the cam, whereby it will cause the switch fingers to close or open at an advanced or retarding stage, thus determining the operation of the motor after the train control from any track circuit has been operated.

In order to prevent over-travel of the switches, that is, in order to insure that the gate arms occupy a pre-selected position, the shaft 62 is provided with a brake drum 268 adapted to be contacted by the spaced shoes 270 and 272 of the brake unit 274. The brake shoes 270 and 272 are pivotally mounted as at 276 and 278 on the spaced levers 280 and 282 pivoted as at 284 and 286 to the support 288. The support 288 is secured to the solenoid 290 connected to the system in a manner to be later described, the solenoid controlling movement of the plunger 292. The plunger 292 is loosely connected through the link 294 to the lever 296, said lever being pivoted as at 298 to the lever 280 and being provided with the arm 300 to which the adjusting rod 302 is pivoted as at 304, the pivot 304 being independent of the lever 280. The adjusting rod 302 is pivoted as at 306 to the lever 282 and is provided with the adjustable head 308 between which the spring 310 is mounted, the spring being adapted to press against the head 312 engaging the head 280.

Figure 6 shows the brake in an off position when the solenoid is energized, moving the plunger 292 inwardly. When the solenoid is de-energized the spring 310 will move the lever 280 downwardly, causing the brake shoe 270 to engage the brake drum. The lever 282 will be moved upwardly to cause the brake shoe 272 to engage the brake drum. When the solenoid is energized inward movement of the plunger will move the lever 296 in a counterclockwise position to permit the lever 282 to drop downwardly, the downward position being limited by the stop 314. Continued movement of the lever 296 will cause the lever 280 to be raised, compressing the spring 310 and bracing the brake shoe 270 out of engagement with the brake drum.

Figure 9 shows a wiring diagram for protection of a crossing of two main railroad tracks and a public highway, using four gates, flash-lights and a bell as protection.

A train entering the track circuit to the left, causes track relay 316 to become de-energized, opening its front contacts and closing its back contacts. This relay, in dropping, closes a circuit from battery 318 to and through limit 75

switches 320 and 322 to contactors 324 and 326, resulting in contactors 324 and 326 becoming energized and closing their respective contacts. The action of closing these contacts results in current flowing to and through fuses 328, to and through thermal protection 330 and to the down winding of the gate motors 332 and 334. Upon current being impressed across these windings, the gate motors 332 and 334 start to operate and continue to do so, bringing their respective gate arms 336 and 338 from a clear up position to a horizontal position, at which time the limit switches 320 and 322 open the circuit to the contactors 324 and 326, causing the current flow to the motors 332 and 334 to be interrupted. This interruption of current flow results in the motors ceasing operation, with a further result of the gate arms 336 and 338 coming to rest.

At the time that the gate arms 336 and 338 came to rest, the limit switches 340 and 342 closed their respective contacts and a circuit was closed from the battery 318, to and through limit switches 340 and 342, to and through limit switches 344 and 346 to contactors 348 and 350, resulting in contactors 348 and 350 closing their respective contacts. The action of closing these contacts results in current flowing to and through fuses 328, to and through thermal protection 330 to the down winding of the gate motors 352 and 354. Upon current being impressed across these windings, the gate motors 352 and 354 start to operate and continue to do so, bringing their respective gate arms 356 and 358 from a clear up position to a horizontal position, at which time the limit switches 344 and 346 open the circuit to the contactors 348 and 350, causing the current flow to motors 352 and 354 to be interrupted. This interruption of current flow results in the motors ceasing to operate, with a further result of the gate arms 356 and 358 coming to rest.

When track relay 316 dropped, it completed a circuit from the battery 318 to and through limit switches 360, 362, 364 and 366 to the bell 369. The bell 369 starts to function and continues to do so until the gate arms have all assumed a horizontal position, at which time the limit switches 360, 362, 364 and 366 open their contacts and the bell ceases to operate.

At the time that track relay 316 dropped, a third circuit was also completed from the battery 318 to flasher relay 368, resulting in the flasher relay 368 operating an armature back and forth, making and breaking circuits to the flasher lights 370 located on each of the gate arms. These lights continue to function until such time as the train moves out of the track circuit.

When the train passes out of the track circuit, track relay 316 becomes energized from battery 372, closing its front contacts and opening its back contacts. This relay, in picking up, opens the circuit to the flashing lights and bell and closes a circuit from the battery 318 to and through limit switches 374, 376, 378, and 380 to contactors 382, 384, 386, and 388, resulting in these contactors becoming energized and closing their respective contacts. The action of closing these contacts results in current flowing to and through fuses 328, to and through thermal protection 330 to the up winding of gate motors 332, 334, 352, and 354. Upon current being impressed across these windings, the gate motors start to operate and continue to do so, bringing the gate arms from a horizontal position to a clear up position, at which time the limit

switches 374, 376, 378, and 380 open the circuit to the contactors 382, 384, 386, and 388, causing the current flow to the motors to be interrupted. This interruption of current flow results in the motors ceasing operation with a further result of the gate arms coming to rest.

When a train enters block 390 from the right it operates the gates in a similar manner as described, the control being from battery 392 and relay 394.

In the assembly of the various parts which make up the gate unit, the individual units described as limit switches and contactors are built into one sub-assembly known as the limit switch, this switch being composed of four limit switches and two contactors. As a sub-assembly it is built into and is part of the mechanism known as the gate unit.

The outstanding achievement resulting from the incorporation of this limit switch into the gate unit is the ease with which gate operation can be controlled. In connection with the control of the gate operation by train movement, it is understood that any device now in use for controlling any type of crossing protection can be used to control the operation of the gate, bell and flashing lights.

One desirable feature of the gate control which is shown in Figure 9 is the retarding, or deferring, of the downward movement of the non-traffic gates, until such time as the traffic gates have reached a horizontal position, or for any period of time between one and ten seconds after the traffic gates start to move downward. This feature has been found to be desirable at a large number of crossings where highway traffic is dense and where it is desired to permit highway traffic, already on the crossing, to move away from that point before bringing the non-traffic gates to a horizontal position.

Another desirable feature which can be incorporated into the control of the gates is that of raising the non-traffic gates before raising the traffic gates, so that when all gates have been raised the highway traffic has an entirely open crossing over which to proceed.

Still another desirable feature, shown in Figure 9 is that of having the bell cease operation after all gates have been brought to a horizontal position. This feature solves the problem where unusual stress has been laid upon the desirability of keeping all noises at a minimum.

Figure 10 shows a wiring diagram of the gate pedestal, using one motor. All instruments within the gate pedestal are shown to correspond with the position of the gate arm when in the down position.

For the purpose of more clearly explaining the sequence of operations, it is assumed that a train or other object is now within the limits which caused the gate to lower. The train, or other object, upon leaving these limits, causes a relay, as described with respect to Figure 9, connected with the rails of the track, to become energized, opening its back contacts and closing its front contacts. Current now flows from the front contact of the relay to terminal 516 in the gate pedestal, and from terminal 516 to and through the contacts of limit switch 518 to the coil of contactor 520. The coil of contactor 520 is energized and attracts to its pole face an armature upon which is mounted an assembly of contacts 522 and 524. Before these contacts reach the pole face of the contactor coil 520 their motion is arrested by contact with studs 526 and 528. 75

The contact between contacts 522 and 524 and studs 526 and 528 serves to introduce a path from terminal 530 to and through contact 524 and stud 528 and to the coil of brake 290 and from terminal 530 to and through contact 522 and stud 526 to motor terminal 532 of motor 534. Terminal 522 having already been connected to an external source of energy, the brake coil 290 and the motor terminal 532 of motor 534 become energized. The brake coil 290 has connected to it (not shown in the drawings—see Figure 6) an assembly of brake shoes which rest against a drum preventing any motion of the gate mechanism, but which are attracted away from the drum and toward the pole face of brake coil 290 when the brake coil is energized. Motor terminal 532 is connected to an internal winding in the motor, this winding causing rotation of the motor in a direction which causes lowering of the gate arm. Rotation of motor 534 is further transmitted to the switch cams 537, 536, 518, and 538, these cams rotating in unison, but in a direction opposite that when the gate arm was raising. When the flattened surface of switch cam 536 is brought around to a position similar to that as shown in the drawings, the inherent pressure 10 in the lower switch spring causes it to pull away from the upper spring, thus opening the circuit from terminal 540 to contactor 542 and causing current flow to that unit to be interrupted. When current ceases to flow to contactor 542, the inherent pressure in contacts 544 and 546 causes the armature assembly to drop away from studs 548 and 550, thus interrupting the flow of current from terminal 530 to motor terminal 552 and brake coil 290. The absence of current at motor 20 terminal 552 results in the motor ceasing to operate, while the interruption of current flow to brake coil 290 causes the coil to become deenergized, allowing the pressure of a spring (part of the brake shoe assembly) to pull the brake shoe 25 assembly away from the pole face of the brake coil and causing the brake shoes to come in contact with the brake drum, instantly stopping further movement of the gate mechanism and the gate arm. 30

Figure 11 shows a wiring diagram of the gate pedestal using both an A. C. motor 554 and a D. C. motor 556. Normal operation of the A. C. motor is the same as described previously, the D. C. motor being employed as motive power only 35 when the source of A. C. fails.

For the purpose of more clearly explaining the sequence of operations, it is assumed that a train is now within the limits which caused the gate to lower. The train upon leaving these limits 40 causes a relay connected with the rails of the track to become energized, opening its back contacts and closing its front contacts. Current now flows from the front contact of the relay to terminal 516 in the gate pedestal, and through the 45 contacts of limit switch 518 and to the coil of contactor 520. The coil of contactor 520, upon energy being impressed across its terminals, is energized and attracts to its pole face an armature upon which is mounted an assembly of contacts 522, 524 and 526. Before these contacts reach the pole face of the contactor coil 520, their motion is arrested by contact with studs 548 and 550. The contact between contacts 544 and 546 and studs 548 and 550 serves to introduce a path from terminal 530 to and through contact 546 and stud 550 and to the coil of brake 290 and from the terminal 530 to and through contact 544 and stud 548 to motor terminal 552 of motor 534. Terminal 530, having already been connected to an external source of energy, the brake coil 290 and the motor terminal 552 become energized. The brake coil 290 has connected to it (not shown in the drawings) an assembly of brake shoes which rest against a brake drum, preventing any motion of the gate mechanism, but which are attracted away from the drum and towards the pole face of brake coil 290 when said brake coil is energized. Motor 70

of switch cam 518 is brought around to a position similar to that of cams 537 and 536, the inherent pressure in the lower switch spring causes it to pull away from the upper spring, thus opening 5 the circuit from terminal 516 to contactor 520 and causing flow to that unit to be interrupted. When current ceases to flow to contactor 520, the inherent pressure in contacts 522, 524 and 554 10 causes the armature assembly to drop away from studs 526, 528 and 560, thus interrupting the flow of current from terminal 562 to brake coil 290, and from terminal 530 to motor terminal 532 of motor 534. The absence of current at motor terminal 532 of motor 534 results in the motor ceasing 15 to operate, while the interruption of current flow to brake coil 290 causes that coil to become deenergized, allowing the pressure of a spring (part of the brake shoe assembly) to pull the brake shoe assembly away from the pole face of the brake coil 290 and causing the brake shoes to come in contact with the brake drum, instantly 20 stopping further movement of the gate mechanism and the gate arm.

To again lower the gate arm, the track relay 25 must become deenergized, opening its front contacts and closing its back contacts. Current now flows from the back contact of the relay to terminal 540 in the gate pedestal, from terminal 540 to and through limit switch 536 to contactor coil 30 542. (Limit switch 536 by virtue of its rotation when the gate arm was rising has now assumed a position similar to limit switches 518 and 538.) The coil of contactor 542, upon energy being impressed across its terminals, is energized and attracts to its pole face an armature, upon which is mounted an assembly of contacts 544, 546 and 566. Before these contacts reach the pole face of the contactor coil 542, their motion is arrested by contact with studs 548, 550, and 568. The 35 contact between contact 546 and stud 550 serves to introduce a path from terminal 562 to and through contact 546 and stud 550 and to the coil of brake 290. Contact 544 and stud 548 create a path for current from terminal 530 to and 40 through contact 544 and stud 548 to motor terminal 552 of motor 534. Terminals 562 and 530 having already been connected to an external source of energy, the brake coil 290 and the motor terminal 552 of motor 534 become energized. 45 Terminal 564, connected with contact 566, does not have current impressed upon it until the A. C. fails when terminal 564 is energized and terminal 530 is deenergized. Motor terminal 552 of motor 534 is connected to an internal winding in the 50 motor, this winding causing rotation of the motor in a direction which causes lowering of the gate arm. Rotation of the motor is further transmitted to the switch cams 537, 536, 518, and 538, these cams rotating in unison. When the 55 flattened surface of switch cam 536 is brought around to a position as shown in the drawings, the inherent pressure in the lower switch spring causes it to pull away from the upper spring, thus opening the circuit from terminal 540 to contactor 60 542 and causing current flow to that unit to be interrupted. When current ceases to flow to contactor 542, the inherent pressure in contacts 544, 546, and 566 causes the armature assembly to drop away from studs 548, 550, and 568, thus 65 interrupting the flow of current from terminal 562 to brake coil 290 and from terminal 530 to motor terminal 552 of motor 534. The absence of current at motor terminal 552 results in the motor ceasing to operate, while the interruption of current 70 flow to brake coil 290 causes that coil to be-

come deenergized, allowing the pressure of a spring (part of the brake shoe assembly) to pull the brake shoe assembly away from the pole face of the brake coil 290 and causing the brake shoes to come in contact with the brake drum, instantly 5 stopping further movement of the gate mechanism and the gate arm.

Motor 570 is provided to allow operation of the gate unit should the source of energy supplied to the A. C. motor 534 fail. Both motors are direct- 10 connected to the gate mechanism through the medium of chains, sprockets and gears, as already described; the two motor sprockets and the driven sprocket forming a triangle, with the motor sprockets assuming the position of the two lower 15 angles. Regardless of the source of external energy applied (either 30 volts D. C. or 110 volts A. C.), both motors rotate at all times when the gate is in operation. In the event of a power failure of the A. C. a suitable relay located externally of the gate becomes deenergized, opening its front contacts through which the A. C. flowed, and closing its back contacts, causing 30 volts of D. C. to flow to terminal 564 in the gate pedestal. Terminal 530 is now deenergized and no current 20 flows at this point. Terminal 562 remains energized with 30 volts of D. C.

For the purpose of more clearly explaining the sequence of operations, it is assumed that a train or other object is now within the limits which 30 caused the gate to lower. The train, or other object, upon leaving these limits causes a relay connected with the rails of the track to become energized, opening its back contacts and closing its front contacts. Current now flows from the 35 front contact of the relay to terminal 516 in the gate pedestal, from terminal 516 to and through the contacts of limit switch 518 and to the coil of contactor 520. The coil of contactor 520, upon energy being impressed across its terminals, is 40 energized and attracts to its pole face an armature upon which is mounted an assembly of contacts. The operation of the various parts is, then, similar in up and down positions as described with respect to the A. C. motor 534.

Figure 12 shows a wiring diagram of the gate pedestal using one motor. All instruments within the gate pedestal are shown to correspond with the gate arm when in the down position.

For the purpose of more clearly explaining the 50 sequence of operations, it is assumed that a train is now within the limits which caused the gate to lower. The train or other object, upon leaving these limits, causes a relay connected with the rails of the track to become energized, opening 55 its back contacts and closing its front contacts. Current now flows from the front contact of the relay to lower terminal 672 in the gate pedestal, from lower terminal 672 to and through the contacts of limit switch 674 and to the coil of contactor 676. The coil of contactor 676, upon energy being impressed across its terminals, is energized and attracts to its pole face an armature upon which is mounted an assembly of contacts 678 and 680. Before these contacts reach the 65 pole face of the contactor coil 676 their motion is arrested by contact with studs 682 and 684. The contact between contact 678 and stud 682 serves to introduce a path from lower terminal 686 to and through contact 678 and stud 682 to upper terminal 688 and to motor terminal 690 of motor 692. Lower terminal 686, having already been connected to an external source of energy, motor terminal 690 of motor 692 is now energized. Motor terminal 690 of the motor is connected to 70 75

an internal winding in the motor, this winding causing rotation of the motor in a direction which causes raising of the gate arm. Rotation of the motor is further transmitted to the switch cams 5 694, 696, 674, and 698, these cams rotating in unison. When the flattened surface of switch cam 674 is brought around to a position similar to that of cams 694 and 696, the inherent pressure in the lower switch spring causes it to pull away from 10 the upper spring, thus opening the circuit from lower terminal 672 to contactor 676, and causing current flow to that unit to be interrupted. When current ceases to flow to contactor 676 the inherent pressure in contacts 678 and 680 causes 15 the armature assembly to drop away from studs 682 and 684, thus interrupting the flow of current from lower terminal 686 to the motor.

Contact 680 and stud 684 of contactor coil 676 are not used in this wiring diagram.

20 To again lower the gate arm the track relay must become deenergized, opening its front contacts and closing its back contacts. Current now flows from the back contact of the relay to lower terminal 600 in the gate pedestal, from lower terminal 600 to and through limit switch 694 to contactor coil 602. (Limit switch 694, by virtue of its rotation when the gate arm was rising, has now assumed a position similar to limit switches 674 and 698.) The coil of contactor 602, upon 25 energy being impressed across its terminals, is energized and attracts to its pole face an armature upon which is mounted an assembly of contacts 604 and 606. Before these contacts reach the pole face of contactor coil 602 their motion is arrested by contact with studs 608 and 610. The contact between contact 604 and stud 608 serves to introduce a path from lower terminal 686 to and through contact 604 and stud 608 to upper terminal 612 and to motor terminal 614 of 30 motor 692. Terminal 686, having already been connected to an external source of energy, motor terminal 614 is now energized, causing rotation of the motor in a direction which causes lowering of the gate arm. Rotation of motor 692 is further transmitted to switch cams 694, 696, 674, and 698, these cams rotating in unison, but in a direction opposite that when the gate arm was raising. When the flattened surface of switch cam 694 is brought around to a position similar 35 to that as shown in the drawings, the inherent pressure in the lower switch spring causes it to pull away from the upper spring, thus opening the circuit from lower terminal 600 to contactor 602 and causing current flow to that unit to be interrupted. When current ceases to flow to contactor 602 the inherent pressure in contacts 604 and 606 causes the armature assembly to drop away from studs 608 and 610, thus interrupting the flow of current from lower terminal 686 to motor terminal 614. The absence of current at motor terminal 614 results in the motor ceasing to operate, allowing the gate arm to come to rest. 40

Contact 606 and stud 610 of contactor 602 are not used in this wiring diagram.

45 Figure 13 shows a wiring diagram of the gate pedestal using both an A. C. motor 692 and a D. C. motor 616. Normal operation of the A. C. motor 692 is the same as described previously, the D. C. motor 616 being employed as motive power only 50 when the A. C. fails. Motor 616 is provided to allow operation of the gate unit should the source of energy, supplied to the A. C. motor, fail. Both motors are direct-connected to the gate mechanism through the medium of gears. Regardless 55 of the source of external energy applied (either 60

volts D. C. or 110 volts A. C.), both motors rotate at all times when the gate is in operation. In the event of a power failure of the A. C., a suitable relay, located externally of the gate, becomes deenergized, opening its front contacts through 5 which the A. C. flowed and closing its back contacts causing 30 volts of D. C. to flow to lower terminal 618 in the gate pedestal. Lower terminal 686 is now deenergized and no current flows at this point. 10

For the purpose of more clearly explaining the sequence of operations, it is assumed that a train is now within the limits which caused the gate to lower. The train, upon leaving these limits, causes a relay connected with the rails of the 15 track to become energized, opening its back contacts and closing its front contacts. Current now flows from the front contact of the relay to lower terminal 672 in the gate pedestal, from lower terminal 672 to and through the contacts of 20 limit switch 674 and to the coil of contactor 676. The coil of contactor 676, upon energy being impressed across its terminals, is energized and attracts to its pole face an armature upon which is mounted an assembly of contacts 678 and 680. 25 Before these contacts reach the pole face of the contactor coil 676 their motion is arrested by contact with studs 682 and 684. The contact between contact 680 and stud 684 serves to introduce a path from lower terminal 618 to and 30 through said contact and stud to upper terminal 620 and to motor terminal 622 of motor 616. Lower terminal 618 having already been connected to an external source of energy (30 volts of D. C.), motor terminal 622 is energized. Lower 35 terminal 686, connected with contact 678, does not have current impressed upon it, since this source of energy has failed. Motor terminal 622 is connected to an internal winding in the motor, this winding causing rotation of the motor in a 40 direction which causes raising of the gate arm. Rotation of motor 616 is further transmitted to the switch cams 694, 696, 674, and 698, these cams rotating in unison. When the flattened surface of switch cam 674 is brought around to a position 45 similar to that of cams 694 and 696, the inherent pressure in the lower switch spring causes it to pull away from the upper spring, thus opening the circuit from lower terminal 672 to contactor 676 and causing current flow to that unit 50 to be interrupted. When current ceases to flow to contactor 676, the inherent pressure in contacts 678 and 680 causes the armature assembly to drop away from studs 682 and 684, thus interrupting the flow of current from lower terminal 55 618 to motor terminal 622. The absence of current at motor terminal 622 results in the motor ceasing to operate, allowing the gate arm to come to rest.

To again lower the gate arm, the track relay 60 must become deenergized, opening its front contacts and closing its back contacts. Current now flows from the back contact of the relay to lower terminal 600 in the gate pedestal, from lower terminal 600 to and through limit switch 694 to 65 contactor coil 602. (Limit switch 694 by virtue of its rotation when the gate arm was rising has now assumed a position similar to limit switches 674 and 678.) The coil of contactor 602, upon energy being impressed across its terminals, is 70 energized and attracts to its pole face an armature upon which is mounted an assembly of contacts 604 and 606. Before these contacts reach the pole face of the contactor coil their motion is arrested by contact with studs 608 and 610. The 75

contact between contact 606 and stud 610 serves to introduce a path from lower terminal 618 to and through contact 606 and stud 610, to upper terminal 624 and to motor terminal 626 of motor 616. Lower terminal 618 having already been connected to an external source of energy (30 volts of D. C.), motor terminal 626 of motor 616 is energized. Lower terminal 606, connected with contact 604, does not have current impressed upon it, since this source of energy has failed. Motor terminal 626 is connected to an internal winding in the motor, this winding causing rotation in a direction which causes lowering of the gate arm. Rotation of motor 616 is further transmitted to the switch cams, these cams rotating in unison. When the flattened surface of switch cam 694 is brought around to a position similar to that as shown in the drawings, the inherent pressure in the lower switch spring causes it to pull away from the upper spring, thus opening the circuit from lower terminal 600 to contactor 602, and causing current flow to that unit to be interrupted. When current ceases to flow to contactor 602, the inherent pressure in contacts 604 and 606 causes the armature assem-

bly to drop away from studs 608 and 610, thus interrupting the flow of current from lower terminal 618 to motor terminal 626, allowing the gate arm to come to rest.

Limit switches 696 and 698 serve no purpose in the control of the gate mechanism, but are supplied as part of the regular equipment to care for auxiliary circuits which might be thought advisable by the purchaser.

It is to be understood that we do not wish to be limited by the exact embodiments of the device shown, which are merely by way of illustration and not limitation, as various and other forms of the device will of course be apparent to those skilled in the art without departing from the spirit of the invention or the scope of the claim.

We claim:

In a crossing gate, a gate arm swingable both vertically and horizontally, means for raising the gate, and means preventing the raising of the gate throughout a predetermined horizontal travel of the gate.

HARRY R. BEHNKE.
WILLIAM M. LOSER.

25

CERTIFICATE OF CORRECTION.

Patent No. 2,054,788.

September 22, 1936.

HARRY R. BEHNKE, ET AL.

It is hereby certified that the name of the assignee in the above numbered patent was erroneously written and printed as "M. Mayhill Smith" whereas said name should have been written and printed as M. Mayhall Smith, of Chicago, Illinois, assignee by mesne assignments, as shown by the records of this office; and that the said Letters Patent should be read with this correction therein that the same may conform to the record of the case in the Patent Office.

Signed and sealed this 8th day of December, A. D. 1936.

(Seal)

Acting Commissioner of Patents.
